THREE-COLOR WRITING IMPLEMENT

Paul Kollsman, New York, N. Y.

Application April 12, 1949, Serial No. 86,939

2 Claims. (Cl. 120—42.12)

1

This invention relates to improvements in writing implements of the type permitting the writer to choose between several colors.

The idea of providing in a single writing implement a plurality of colors optionally usable by the writer is basically not novel. For example, multi-color pencils have been known for many years in which a number of projectable and retractable points of different colors is arranged of which one point at a time may be projected into writing position while the other points remain retracted. Change from one color to another in this type of pencil involves manipulation of the retracting and projecting mechanism which requires a certain amount of time depending on the dexterity of the writer.

Multi-color fountain pens have also been proposed in which a plurality of permanent nibs at one end are fed from an equal number of ink reservoirs. The proposed arrangement has several disadvantages. First among these is the difficulty of the writer to see exactly what he is writing since the two nibs not in use obscure the one underneath which is being used. Another disadvantage of the proposed arrangement is the well known tendency of an uncovered nib exposed to air to dry up in a degree sufficient to impede the flow of ink from the nib when the nib is taken into use after temporary non-use. Another disadvantage of the aforementioned triple nib fountain pen is the difficulty of bringing each nib into proper writing position due to the fact that it is obscured by the two nibs above it.

The present invention provides an improved multi-color writing implement, more particularly of the three-color type, which is free from the aforementioned disadvantages. The novel and improved implement is ready for instantaneous use at all times, permits instantaneous changing from one color to another without manipulation of any mechanism and is so constructed that the writing is not obscured. The improved implement includes provision for automatic and correct indexing of its several writing points and provides means for visible indication of the color of the point which happens to be in writing position. This is achieved in an ingenious arrangement of the color markings such that it is practically impossible to cover up the marks regardless of how the implement is being held, thus permitting checking of the color without necessity of moving a single finger from the proper writing position with respect to the implement.

The various objects, features and advantages of this invention will appear more fully from the detailed description which follows accompanied

5 by drawings showing, for the purpose of illustration, a preferred embodiment of the invention. The invention also consists in certain new and original features of construction and combination of elements hereinafter set forth and claimed.

10 Although the characteristic features of this invention which are believed to be novel will be particularly pointed out in the claims appended hereto, the invention itself, its objects and advantages, and the manner in which it may be carried out may be better understood by referring to the following description taken in connection with the accompanying drawings forming a part of it in which:

Figure 1 is a sectional side view of a three color ball point pen embodying the invention;

Figure 2 is a cross sectional view of the pen, the section being taken on line 2—2 of Figure 1;

20 Figure 3 is a front view of the pen of Figure 1 with the cap removed;

Figure 4 is a side view of the pen in writing position;

Figure 5 is a perspective view of the pen of Figure 4 with the cap removed; and

25 Figure 6 is a sample of double line writing produced by the novel pen.

In the following description and in the claims various details will be identified by specific names for convenience. The names, however, are intended to be as generic in their application as the art will permit. Corresponding reference characters refer to corresponding parts in the several figures of the drawings.

30 In the drawings accompanying, and forming part of, this specification, certain specific disclosure of the invention is made for the purpose of explanation of broader aspects of the invention, but it is understood that the details may be modified in various respects without departure from the broad principles of the invention, and that the invention may be applied to other structures than the ones shown.

35 The ball point pen shown in Figures 1 to 3 comprises a hollow barrel 11 having three substantially flat outer surfaces 12, 13 and 14 adapted to rest on the thumb, the index finger and the middle finger of the user. The three surfaces 12, 13 and 14 lie at an angle of substantially 120° with respect to one another and have ridges 15, 40 16 and 17 between them.

45 The barrel 11 is tapered towards either end, the front taper being indicated at 18 and the rear taper at 19. A shoulder 20 lies between the tapered front portion and the tapered rear portion at the point of largest circumference of

the barrel. This shoulder 20 provides a positive stop for a cap 21 preferably of metal which may be frictionally attached to the barrel by telescoping it over the barrel until it comes to rest against the shoulder. The cap 21 has a configuration, in cross section, corresponding substantially to that of the barrel. It covers the front portion of the barrel if attached as shown in Figure 1, and it provides an extension of the barrel, if it is attached to the rear portion, as is also shown in Figure 4. It is preferable to locate the shoulder 20 within the rear half portion of the barrel rather than at or near its center portion in order to obtain a substantial extension in length of the pen when the cap is attached to the rear portion for writing, and to obtain a substantial reduction of the total length of the pen for convenient carrying of the pen when the cap is attached to the front portion.

The interior of the barrel is provided with three separate ink compartments which may or may not be formed of the material of the barrel itself. Preferably the ink compartments are made separate from the barrel. For this purpose the barrel may be provided with a single interior cavity 22 of substantially clover leaf shape in cross section accommodating three substantially cylindrical cartridges 23, 24 and 25. These cartridges form the subject matter of applicant's copending application Serial Number 86,940, filed April 12, 1949, now Patent Number 2,585,016.

Taking cartridge 23 as an illustrative example of the construction of the cartridges, each cartridge comprises a substantially cylindrical shell 26 the forward end of which is closed by an end wall 27 from which a duct 28 extends. The duct 28 terminates in a ball socket 29 within which a ball 30 is mounted with freedom to rotate in the socket. The socket 29 is preferably offset with respect to the axis of the shell 26. A portion of the ball 30 is exposed, the exposed portion lying substantially at right angles with respect to the axis of the shell 26.

The cartridges 23, 24 and 25 are preferably arranged within the barrel 11 in wall-to-wall contact with one another and are held within the barrel portions of the cavity of substantially the same radius as the radius of the cartridge shells. In this manner a definite placement of the cartridges in the barrel 11 is insured with respect to the surfaces 12, 13 and 14.

The interior cavity 22 of the barrel includes a front shoulder 31 extending substantially normal with respect to the axis of the barrel. The interior cavity extends beyond the shoulder 31 with a portion 32 of reduced width terminating in a front aperture 33 of substantially triangular shape. The points of the triangle of the aperture 33 are preferably rounded to fit the outside of the ducts 28 extending from the three cartridges. Referring to Figure 3 the ball points 30, 34 and 35 in their respective sockets 29, 36 and 37 are shown to form a triangle inverted with respect to the triangle formed by the sides 12, 13 and 14 of the barrel.

The front portions of the cartridge ducts, or their respective sockets 29, 36 and 37 are preferably in wall-to-wall contact and extend slightly beyond the front end 38 of the barrel.

The three cartridges are preferably identical in dimension, so that the three ball points project an equal distance from the barrel, while the rear ends 39 of the cartridges also lie in one plane.

The cartridges are securely held in the barrel by a threaded plug 39 having a vent passage

50 therethrough and bearing against the rear ends of the cartridges. The threads 41 of the plug fit into three threaded peripheral portions of the barrel, one portion being shown at 42, the diametrically opposite portion of the barrel being without threads due to the clover-leaf shape of the interior cavity, the unthreaded portion being shown at 43.

The barrel is provided with three recesses 43, 44 and 45 into which color markers 46, 47 and 48 are inserted to indicate the color of the ink contained in cartridges 23, 24 and 25 respectively. Thus the color marker 46 is associated with the cartridge 23. This marker may be a strip of red plastic embedded in the recess 43 to indicate that the cartridge 23 contains red ink. The mark 47 is associated with the cartridge 24. It may be a strip of green plastic material to indicate that the cartridge 24 contains green ink. Finally the marker 48 may be black to indicate that its associate cartridge contains black ink.

The use of the pen is obvious from the foregoing description. Being of substantially triangular cross section the barrel 11 rests securely between the thumb, index and middle finger of the user's hand in a position in which one of the ball points lies bottom-most in writing position. In the position in which the pen is held in the user's hand a ridge with its color marking faces the user and indicates the color of the ball point which is in writing position. Since the color marker extends along the ridge rather than along the flattened surface of the barrel it is never obstructed by the writer's fingers.

If a change in color is desired the pen is simply rotated in the writer's hand and again comes to rest automatically in a proper writing position due to the automatic indexing achieved by the unique relationship of the flattened surfaces with respect to the ball points.

The shape of the barrel offers the advantages of preventing the pen from rolling on the flat or inclined surface and automatically insures the proper location of a writing point with respect to the writing surface, so that an accidental contact of more than one point with writing surface is prevented.

Nevertheless, due to the unique construction and arrangement of the three writing points, it is possible to bring two points to bear on the writing surface at one time, if this is desired by the writer for the purpose of achieving special decorative writing effects as shown in Figure 6. This effect is relatively easily produced by holding the pen in such a way that the ridges, rather than the flat surfaces, rest against the fingers. This position is not uncomfortable, and it is quite easy to move the barrel into the proper position for double-line writing. Nevertheless, unless it is specifically intended to produce a double-line effect the barrel moves naturally and automatically into a position in which only one point contacts the writing surface, the color being indicated by the ridge marking.

In the event of decorative double-line writing the ridge marks again are useful for determining the ink colors about to be used. In the double-line position two markers are visible to the writer instead of one and the corresponding two colors are the ones which appear on the writing surface.

The improved writing implement embodying the invention is very convenient to carry since it can be made extremely short for carrying in

a pocket, vest pocket, or pocketbook with the cap placed over the front end to cover the points. Its length is greatly extended when the cap is placed on the rear end.

The writing implement permits of six different color choices, including three single colors and three two-color combinations. The pen is attractive in appearance, simple to manufacture and is extremely convenient to use since no mechanical adjustments or manipulations are required for changing from one color to another.

One of its major features is the automatic indexing of the points, accomplished by the unique shape of the barrel in combination with the angular arrangement of the three points with respect to the surfaces of the barrel resting against the writer's fingers. The color markings are unobstructed at all times and indicate the ink color regardless of whether the pen is being held in a position for single-line writing or whether it is being used to produce decorative double-lines.

Empty cartridges are easily replaced either one by one or all at one time. The clover-leaf-shaped cross section of the interior cavity of the barrel aids in leading the cartridges into proper position. The reduced front portion 32 of the cavity aids in guiding the offset duct portions of the cartridges into proper seating position.

Since the front end of the pen containing the three writing points is extremely small the point or points temporarily not used do not obstruct the writing surface and are comparable in shape and size to the point of conventional single color ball point pen.

The use of the ball points in the implement gives the advantage of instantaneous starting. Thus the troublesome drying up commonly found in fountain pens does not occur.

For the foregoing it is apparent that the invention provides an extremely useful writing implement whose features are unmatched by known or heretofore proposed multi-color writing implements of the pencil or fountain pen type.

What is claimed is:

1. A three-color writing implement comprising in combination, a hollow barrel having three substantially flat outer surfaces adapted to rest on the thumb, index finger and middle finger of a writer, the said surfaces lying at an angle of substantially 60 degrees with respect to one another; three removable ink cartridges lying in said barrel in wall-to-wall contact with one another, each of said cartridges having an extension of a smaller diameter than the diameter of

the respective cartridges, said extension terminating in a ball point and socket extending from the forward ends of the barrel, said extensions lying in wall-to-wall contact with one another at said sockets, said barrel having provision for positively engaging said extensions in a position in which the three extensions form corners of a triangle inverted with respect to the triangle formed by said three surfaces; a plug attachable to the rearward end of the barrel for engaging the ends of said cartridges to hold them in the position in which their extensions project from the forward end of the barrel; and color markings on the barrel, one of the markings facing upwardly to indicate the color of the ink of the respective cartridge whose extension is lowermost and in writing position.

2. A three-color writing implement comprising in combination, a hollow barrel having three substantially flat outer surfaces adapted to rest on the thumb, index finger and middle finger of a writer, the said surfaces lying at an angle of substantially 60 degrees with respect to one another, there being ridges between adjacent surfaces, the barrel comprising three separate ink compartments; a tubular projection associated with, and in communication with, each of said compartments, said projection terminating in a ball point and socket extending from the forward end of the barrel, said sockets being of smaller diameter than the respective cartridges of which they form a part, the three sockets lying in wall to wall contact and forming corners of a triangle inverted with respect to the triangle formed by said three surfaces; and color markings on the ridges of the barrel to indicate the color of the ink in the respective compartments whose extension and ball point is lowermost and in writing position in the position in which the implement is being held in the writer's hand.
